UNITED STATES PATENT OFFICE

95,262

DESIGN FOR A BOTTLE

Abraham Lincoln Key, Great Kills, Staten Island, N. Y., assignor to Hazel-Atlas Glass Company, Wheeling, W. Va., a corporation of West Virginia

Application February 13, 1935, Serial No. 55,397

Term of patent 14 years

To whom it may concern:

Be it known that I, Abraham L. Key, a citizen of the United States, residing at Great Kills, Staten Island, in the county of Richmond and State of New York, have invented a new, original, and ornamental Design for a Bottle, of which the following is a specification, reference being had to the accompanying drawing, forming part thereof.

The figure is an elevational view of the bottle showing my new design.

I claim:

The ornamental design for a bottle, as shown.

ABRAHAM LINCOLN KEY.
